(57) **CLAIM**

The ornamental design for a pooper scooper, as shown and described.

DESCRIPTION

FIG. 1 is a top, front perspective view of a pooper scooper showing my new design; showing my new design;

FIG. 2 is a top, rear perspective view thereof;

FIG. 3 is a top view thereof;

FIG. 4 is a bottom view thereof;

FIG. 5 is a left side view thereof;

FIG. 6 is a front view thereof; and,

FIG. 7 is a rear view thereof.

The broken lines represent portions of the pooper scooper that show features that form no part of the claimed design.

1 Claim, 7 Drawing Sheets
